Primary Examiner — Holly E Thurman(74) Attorney, Agent, or Firm — Ladas & Parry LLP(57) CLAIM

The ornamental design for a handbag, as shown and described.

DESCRIPTION

The broken lines in the drawings depict a strap and forms no part of the claimed design. The broken lines along the perimeter of the handbag depicts decorative stitching and forms part of the claimed design.
